DUAL BLADE UNIT FOR A SAFETY RAZOR

Francis W. Dorion, Jr., Hingham, Mass., assignor to The Gillette Company, Boston, Mass.

Filed Mar. 15, 1971, Ser. No. 124,620

Term of patent 14 years

Int. Cl. D28—03

U.S. Cl. D95—3

Fig. 1

Fig. 2

Fig. 3

Fig. 4

Fig. 5

Fig. 6

FIG. 1 is a perspective view of a dual blade unit for a safety razor showing my new design;
FIG. 2 is a front elevational view thereof;
FIG. 3 is a back elevational view thereof;
FIG. 4 is a top plan view thereof;
FIG. 5 is a bottom plan view thereof; and
FIG. 6 is an end elevational view, the opposite end being substantially a mirror image thereof.

I claim:
The ornamental design for a dual blade unit for a safety razor, substantially as shown and described.
